(57) **CLAIM**

The ornamental design for jumper cables with lights, as shown and described.

DESCRIPTION

FIG. 1 is a perspective view of the jumper cables with lights according to the present invention.

FIG. 2 is a left side view of the jumper cables with lights according to the present invention. The right side view is a mirror image of the left side view.

FIG. 3 is a front view of the jumper cables with lights according to the present invention; and,

FIG. 4 is a top view of the jumper cables with lights according to the present invention.

The broken lines in all views are for illustrative purposes only and form no part of the claimed design.
